CLAIM

The ornamental design for a tablet with card reader, as shown and described.

DESCRIPTION

FIG. 1 is a front perspective view of a tablet with card reader;

FIG. 2 is a rear perspective view thereof;

FIG. 3 is a front view of the design of FIG. 1;

FIG. 4 is a rear view of the design of FIG. 1;

FIG. 5 is a top view of the design of FIG. 1;

FIG. 6 is a bottom view of the design of FIG. 1;

FIG. 7 is a left side view of the design of FIG. 1; and,

FIG. 8 is a right side view of the design of FIG. 1.

(Continued)

The broken lines in the drawings depict environmental subject matter only and form no part of the claim.

1 Claim, 6 Drawing Sheets
